UNITED STATES PATENT OFFICE.

FERDINAND MAX EUGEN BLASS, OF MÜLHEIM-ON-THE-RHINE, GERMANY, ASSIGNOR,
BY MESNE ASSIGNMENTS, TO THE CHEMICAL FOUNDATION, INC., A CORPORATION
OF DELAWARE.

DEVICE FOR CHARGING RETORTS.

1,357,487.

Specification of Letters Patent. Patented Nov. 2, 1920.

Application filed November 24, 1915. Serial No. 63,231.

To all whom it may concern:

Be it known that I, FERDINAND MAX EUGEN BLASS, a citizen of the German Empire, and a resident of Mülheim-on-the-Rhine, Germany, have invented certain new and useful Improvements in Devices for Charging Retorts and the like, of which the following is a specification.

My invention relates to devices for charging retorts and the like, as for instance the chambers of coke-ovens, coalite ovens, chemical retorts, lithopone ovens, ovens for roasting pyrites, ovens for oxidizing barium oxide, etc. The object of my present invention is to avoid certain difficulties and defects generally occurring with constructions of this kind used hitherto, and particularly the sticking of the charge to the walls of the retort, the obstruction of the gas passages, the decomposition of the gas produced, with a resulting loss in heating or illuminating power, etc. The improved charging device designed by me makes it possible to operate coke-ovens and the like continuously in a manner satisfying practical requirements. These results are obtained by a novel construction more fully set forth hereinafter and specifically pointed out in the claims, a salient feature of this construction being an arrangement according to which the gases leaving the retort or the like surround entirely a passage or chute through which the fresh fuel is supplied, with a beneficial effect both on the gases and on the fuel, as fully explained below.

Two typical examples of a retort provided with my improvements are illustrated in the accompanying drawings, in which Figure 1 is a vertical section through a portion of an upright-retort oven to which my improved charging device is applied; Fig. 2 is a detail view of the upper portion of Fig. 1, shown upon an enlarged scale, the plane of the section being indicated by the line 2—2 of Fig. 3; Fig. 3 is a vertical section on the line 3—3 of Fig. 2; Fig. 4 is a horizontal section on line 4—4 of Figs. 2 and 3; and Fig. 5 is a vertical section, similar to Fig. 3, through a slightly different form of my invention.

In the accompanying drawings, my improved charging arrangement is shown applied to a coke-oven having upright cham-

bers, such as 10, flaring from top to bottom, this being a well-known type of coke-oven. 55 I desire it to be understood, however, that my invention is applicable to ovens and retorts of other types as well. In the side walls of the chambers 10 are provided the heating flues 11 of any well-known or approved construction and arrangement. On top of the chamber 10 is secured a casing 12 the interior of which communicates with the said chamber, and at a suitable point of its outer portion, said casing is provided 60 with an outlet through which the gases produced by the distillation of the fuel in the chamber 10, may pass to a pipe for conveying them to the usual apparatus where they are treated further. In the construction 70 shown in Figs. 1 to 4, the pipe 13 leads from the outer portion of the casing 12 at the top, while in Fig. 5 the outlet pipe 13' is connected with the outer portion of the casing at the side. To the top plate 12' of the casing 12 is secured a funnel or charging chute 14, the lower end of which extends into the upper portion of the chamber 10. This lower or discharge portion of the chute is preferably of a cross section similar 80 to that of the chamber 10; thus, Fig. 4 shows that both the chamber 10 and the lower or discharge portion of the chute 14 are oblong in cross section. The upper end of the chute is adapted to register with any 85 suitable charging hopper or the like, as indicated at 15 in Fig. 1. At the upper end of the chute I arrange a suitable valve or damper (not shown) adapted to be operated by a handle 14', and normally closed to prevent the escape of gas therethrough; the hopper 15 is provided at its lower portion with a valve or damper operated by a suitable handle 15' and normally closed, to be opened only when fuel is to be transferred 95 from the hopper to one of the chutes 14. The gas-discharge pipes 13, 13' may be connected with a gas main 16. In Figs. 1 to 4, the chute 14 is slightly inclined, and placed to one side within the casing 12; in Fig. 5, 100 the chute 14' is located exactly at the center of the casing 12 and chamber 10. The chute 14 is secured in any suitable manner to the casing 12 or its top plate 12', but, except where it passes through said top plate, the 105 chute 14 is spaced from the wall of the cas-

ing so that the gases evolved from the fuel in the chamber 10 will flow upwardly along the chute 14 on every side thereof, that is to say, the lower portion of the chute is 5 surrounded entirely by the gases traveling to the outlet 13 or 13'. At the upper portion of the chamber 10, that is to say, the portion containing the lower end of the chute 14, and at the same level, substantially, as said lower chute end, the walls of 10 said chamber may be made with channels or flues 17 through which a cooling fluid, such as air, may be circulated; for instance, in furnaces employing preheated air to support 15 combustion, the air to be preheated may be conducted through the channels or flues 17. It will also be observed that the lower end of the fuel chute 14 is at a level distinctly above the level of the uppermost 20 heating flues 11, and, since said lower end of the chute practically determines the level of the upper surface of the fuel charge in the chamber 10, it follows that the temperature is relatively moderate at the surface 25 level of the fuel charge in said chamber, thus avoiding the danger of decomposition of the gas which leaves the charge at said level. The temperature is thus kept moderate at this point by two factors, viz.: 30 the arrangement of the lower end of the chute 14 above the level of the uppermost heating channels 11, and, second, the arrangement of said lower chute end at the same level with the cooling channels 17. 35 At suitable points, I may provide openings (normally closed by covers 18) for inspecting or cleaning the interior of the apparatus, or for pushing the fuel down when required.

40 The fuel charged into the hopper 15 and transferred to the chute 14 in any usual or approved manner, slides down into the chamber 10, which is the working chamber of the oven or retort. The fuel level in the 45 chamber 10 will remain constant and substantially even with the lower end of the chute 14, as long as there is any fuel left in said chute, it being understood that at the beginning the chute 14 is filled to the 50 top, and that it is refilled before all the contents of the chute have been discharged into the working chamber 10. A continuous operation is thus obtained, with a constant fuel level and uniform conditions for the 55 production of gas. The fuel in the chute forms a seal, and as distillation progresses, the gases evolved in the portion of the chamber below the chute 14 will rise around the chute in the upper part of the chamber and 60 in the casing 12. These gases will be kept relatively cool, since the outer wall of the casing 12 is exposed to the surrounding air, even if no cooling medium is circulated through the channels 17. Of course, the 65 action is more efficient when the cooling channels 17 are employed. The gases, when they are kept comparatively cool, as described, will not be liable to decomposition within the upper part of the working chamber 10 and on their way to the outlet 13 or 70 13'. Another advantage is that the gases can rise uniformly from the mass undergoing distillation, along the entire contour of the chamber 10, since the chute 14 does not reach close enough to the walls of said 75 chamber to obstruct the upward passage of the gases at any point of said walls. The cooling effect secured by exposing the outer surface of the casing to the surrounding air, may be increased further by expedients such as providing external ribs to enlarge the surface of the casing thus exposed, or causing water to flow over said outer surface. A further advantage resulting from my improved construction is that the hopper 15 80 and the chute 14 are kept comparatively cool, so that the fuel contained in said supply members will not undergo distillation until it issues from the lower end of said chute. Sticking of the charge in the chute 85 is thus avoided, and a continuous operation may be conducted without difficulty, if desired, in which case the fuel is supplied continuously through the hopper 15 or its equivalent, and removed continuously at the 90 bottom of the working chamber 10, by means of any usual or approved discharge device such as spiked rotary rollers 19. The gas evolved in the retort is of good heating or lighting capacity, which is due chiefly to 95 the fact that it can rise freely at all points of the periphery or contour of the mass undergoing distillation, and to the fact that undue heating, and resulting decomposition of the gases produced, are avoided in the 100 manner set forth above. There will be no precipitation of heavy tar or pitch such as might obstruct the gas outlet. The recovery of by-products such as tar and ammonia, is 105 exceedingly high when my improved construction is employed, since practically the entirety of these by-products leaves the apparatus with the gases, instead of being deposited in part on the walls of the channels through which the gases pass out. It will 110 be noted particularly that the fresh fuel discharged from the chute 14 is not brought in contact immediately with highly heated surfaces, but the fresh fuel is discharged on the coolest portion of the mass in the working 115 chamber, thus preventing, so far as possible, the undue heating of the material in the supply channels, and the escape of distillation products through the column of fresh fuel 120 in said channels.

125 As I have mentioned above, my invention is not limited in its application to ovens having upright chambers, and while I prefer a continuous operation, an intermittent one may be employed instead.

Various modifications may be made without departing from the nature of my invention as defined in the appended claims.

I claim as my invention:

- 5 1. An oven or the like, provided with a working chamber, and with heating flues in the walls of said chamber, a stationary casing extending upwardly from said chamber and communicating therewith, and exposed to the cooling influence of the surrounding atmosphere, and a material-charging chute secured to and extending within said casing and terminating within said chamber at a material distance below the 10 upper end thereof, said chute being spaced from the walls of the chamber and of the casing on all sides so that the gases rising from the material will surround the said chute entirely, the casing being provided 15 with a gas outlet at its outer portion.
- 10 2. In an oven or the like for the distillation of fuel, provided with an upright working chamber and with heating channels in the walls of said chamber, a fuel-charging 15 chute having its upper portion exteriorly
- 15 of said chamber and its lower portion within said chamber and spaced from the walls thereof, the lower end of said chute being at a level substantially above that of the uppermost heating channel, whereby the 20 temperature will be kept relatively moderate at the upper surface of the fuel which substantially coincides with said lower chute end.
- 20 3. An oven or the like provided with a working chamber, a stationary casing extending upwardly from the said chamber and communicating with the interior thereof, the outer surface of said casing being exposed to the surrounding air, while its inner 25 surface is exposed to the gases rising from said chamber, and a stationary chute extending downwardly through said casing and having its discharge end spaced from the wall of said chamber on all sides, said casing being provided with a gas outlet located 30 externally of the chute.

In testimony whereof I have hereunto affixed my signature.

FERDINAND MAX EUGEN BLASS.
